UNITED STATES PATENT OFFICE.

JEULEOS GAMBLLEE, OF CRESSKILL, NEW JERSEY.

DOOR.

SPECIFICATION forming part of Letters Patent No. 323,658, dated August 4, 1885.

Application filed April 14, 1885. (No model.)

To all whom it may concern:

Be it known that I, JEULEOS GAMBLLEE, of Cresskill, in the county of Bergen and State of New Jersey, have invented a new and Improved Door, of which the following is a full, clear, and exact description.

Reference is to be had to the accompanying drawings, forming a part of this specification, in which similar letters of reference indicate corresponding parts in all the figures.

Figure 1 is a front elevation of a door-casing and door to which my improvement has been applied. Fig. 2 is a sectional elevation of the same taken through the line *xx*, Fig. 1. Fig. 15 3 is a front elevation of the central part of the operating mechanism. Fig. 4 is a sectional plan view of the same taken through the line *yy*, Fig. 3, and showing a part of the door in section. Fig. 5 is a sectional plan view of the 20 same taken through the lines *zz*, Fig. 3, and showing part of the door in section, and with part broken away. Fig. 6 is a sectional elevation of a part of the same taken through the line *ww*, Fig. 3. Fig. 7 is a sectional elevation of a part of the same taken through the 25 line *vv*, Fig. 3.

The object of this invention is to provide doors having top and bottom openings with a mechanism constructed in such a manner that 30 the said openings will be closed as the door is shut and uncovered when the door is opened, that the said mechanism can be so adjusted that the door can be opened and closed without affecting the covers of the openings, and 35 that the openings can be uncovered and closed while the door is shut.

The invention consists in the combination, with a door having top and bottom openings, of slides for closing and uncovering the said 40 openings, and a mechanism for operating the said slides automatically and by hand, as will be hereinafter fully described, and then pointed out in the claims.

A represents the floor of a room; B, the 45 casing of a doorway, and C the door, which is hung with its lower edge a little above the floor A, no threshold being used.

In the lower edge of the bottom bar of the door-frame is formed a groove, D, in which 50 is placed a slide, E, the width of which is equal to the depth of the groove D, so that the

said slide can be drawn up into the said groove to bring its lower edge flush with the lower edge of the door C.

Into a screw-hole in the upper edge of the 55 slide E, or into a nut secured to the said slide, is screwed the lower end of the rod F, so that the said slide E can be adjusted to move out to a greater or less distance below the lower edge of the door, as may be required. With 60 this construction, should the floor be inclined or an obstruction be left upon the floor A within the doorway, the rod F will yield and allow the slide E to take an inclined position. The rod F and slide E are held up by a spiral 65 spring, G, placed upon the said rod, with its lower end resting against the shoulder at the lower end of the groove, in which the said rod is placed, the said shoulder being faced with metal to prevent it from being worn. The upper 70 end of the spring G rests against a shoulder or enlargement of the upper end of the said rod F. In the upper end of the rod F is formed a perforation to receive a pin, H, attached to the forward side of the lower end of 75 the bar I, which slides upon a plate, J, secured in a recess in the middle part of the door C. The upper and lower parts of the sliding bar I are slotted to receive pins K L, attached to the upper and lower parts of the plate J, to 80 keep the said sliding bar I in place as it moves up and down.

To the forward side of the upper ends of the sliding bar I is attached a pin, M, to enter a 85 perforation in the lower end of the rod N, the upper end of which is provided with a screw-thread, and is screwed into a screw-hole in the plate O, or in a lug or nut formed upon or rigidly attached to the said plate O, so that the said plate will be moved up and down by 90 and with the sliding bar I. The plate O slides up and down in a recess in the center bar of the door-frame, and has a number of perforations, P, formed through it for the passage of air.

In the upper parts of the panels of the door C are formed a number of perforations, Q, corresponding in size and shape with the perforations P, and in such positions that when the sliding plate O is drawn down the perforations P Q will register and the air will have a 95 free passage through the upper part of the 100 door.

door, and when the sliding plate O is raised the perforations P will be opposite the spaces between the perforations Q, and the passage of air will be prevented.

5 To the upper part of the sliding bar I is secured the upper end of a spring, R, which is made with a lateral extension on its lower end, which overlaps the upper part of the bar S. The bar S rests and slides on the plate J, and 10 is slotted to receive the pin T, attached to the said plate J to serve as a guide to the said bar S.

To the lower side of the extended lower end of the spring R is attached a pin, U, to enter 15 a hole in the upper part of the sliding bar S, and cause the said bar S to move up and down with the spring R and bar I.

To the lower end of the sliding bar S is pivoted the end of the long arm of the elbow-lever V, which is pivoted at its angle to the 20 plate J.

The short arm of the elbow-lever V projects upward, and has a slot, W, formed in it to receive the flattened neck in the inner 25 end of the rod X.

In the side of the short arm of the elbow-lever V is formed an opening leading into the slot W, so that by sliding the end of the rod X down into the lower end of the slot W 30 the said rod can be disconnected from the said lever. The rod X slides in a hole leading in from the outer edge of the door C, and its outer part is enlarged and has its outer end beveled, as shown in Fig. 5, so that the said 35 rod can be pushed inward by having its outer end come in contact with a plate, Y, attached to the door-jamb.

The outer part of the perforation in which the rod X works is countersunk to receive the 40 enlarged outer part of the said rod X, and to receive the spiral spring Z, placed upon the rod X, with its outer end resting against the shoulder of the said rod, and its inner end resting against the shoulder at the inner end of 45 the countersink of the perforation in which the said rod works, so that the said spring Z, will hold the rod X, pressed outward in position to strike against the plate Y, and the long arm of the elbow lever V, the sliding bars S 50 I, the rods F N, and the slides E O will be raised against the tension of the spring G, uncovering the openings at the bottom and top of the door, and allowing the said door to swing open and shut freely.

55 When the door is shut, the outer end of the rod X strikes against the plate Y, and the said rod is pushed inward, which lowers the long arm of the elbow-lever V and the sliding bars S I, the rods F N, and the slides E 60 O, closing the bottom and top openings of the

door C. The guide-pin K projects to receive and serve as a pivot to the hub of the double cam a, which is made in crescent shape, and has the convex edge of its upper arm beveled upon the outer side to engage with the recessed 65 edge of the spring R, beveled upon the inner side, so that when the said upper arm of the double cam a is turned against the edge of the said spring, the lower end of the said spring will be raised, withdrawing the pin U 70 from the sliding bar S, so that the door can be shut without covering the bottom and top openings of the said door. When the double cam a is turned in the other direction, its lower arm engages with the flange, rib, or shoulder 75 b, formed upon the sliding bar I, and forces the said bar, the rods F N, and the slides E O downward, covering the bottom and top openings of the door. By this construction the slides E O can be adjusted independent of the 80 rod X. c is a key, knob, or other handle, placed upon the hub of the double cam a, and secured in place by a pin, d, passing through the said hub and the shank of the said key, or other suitable means. 85

Having thus described my invention, I claim as new and desire to secure by Letters Patent—

1. The combination, with a door, C, having top and bottom openings, of the slides O E I, the rods N F, connecting the said slides, the 90 spiral spring G, placed upon the lower rod, F, the spring R, attached to the slide I, and having pin U, the sliding bar S, having perforation to receive the said pin U, the elbow-lever V, having its long arm connected with the 95 slide S, and having a slot, W, with side opening in its short arm, the rod X, engaging with the slotted arm of the elbow-lever V, and the spiral spring Z, placed upon the said rod X and pressing it outward, substantially as herein 100 shown and described, whereby the said slides will be operated automatically to cover and uncover the top and bottom openings as the door is closed and opened, as set forth.

2. The combination, with the door C, the 105 central slide, I, connected by the rods N F with the top and bottom slides, O E, and having shoulder b, and the spring R attached to the said slide I, and having its recessed lower end beveled, of the double cam a, having its 110 upper arm beveled, and the key c, secured to the cam-hub, substantially as herein shown and described, whereby the said slides can be thrown out of connection with the rod X, and the said top and bottom slides operated by 115 hand, as set forth.

JEULEOS GAMBLEE.
